DEVICE FOR LIFTING VALVES AND MANHOLE COVERS

Filed Dec. 15, 1932

FIG. 1.

FIG. 2.

FIG. 3.

INVENTOR:

Joseph J. Moylan,

BY

F. G. Fisher,

ATTORNEY.

UNITED STATES PATENT OFFICE

1,933,384

DEVICE FOR LIFTING VALVES AND
MANHOLE COVERS

Joseph J. Moylan, Kansas City, Mo.

Application December 15, 1932
Serial No. 647,423

2 Claims. (Cl. 294—17)

My invention relates to devices for lifting valve covers, manhole covers, sewer covers, and the like, and my object is to provide a simple, durable and efficient device of this character which 5 may be manufactured at small cost and is well adapted for the purpose intended.

Valve covers such as are employed to close the openings in which are located valves on municipal water mains have rather deep flanges to 10 prevent their displacement by vehicles running thereover, and hence such covers can be removed only by lifting them vertically from the openings.

By the use of my device vertical lifting of the 15 cover can be readily accomplished, and in order that the invention may be readily understood reference will now be had to the accompanying drawing in which:

Fig. 1 is a perspective view of the device in 20 position for lifting a cover.

Fig. 2 is a combined side elevation and vertical sectional view of the device in position preparatory to lifting the cover from the opening.

Fig. 3 shows the device after it has lifted the 25 cover from the opening.

Referring in detail to the different parts, 2 designates a pick-like structure comprising a handle 4 and a transverse head 6, which latter has an enlargement 8 intermediate its ends for the 30 reception of one end of the handle 4. The head 6 includes an element 10 which is reduced and slightly bent rearwardly at its lower end to provide a jaw 12.

14 designates a member having a bifurcated 35 end 15 operably connected to the element 10 by suitable means such as a bolt or pivot 16. The member 14 extends forwardly beneath the handle 4 and is provided at its forward end with a downturned jaw 18. The element 10 and the 40 bifurcated end 15 of the member 14 have a plurality of holes 20 and 22, respectively, for the reception of the pivot 16, so that said member 14 may be adjusted upward or downward, or forward or backward upon the element 10 to accommodate covers of different sizes.

A, designates a cover such as is employed in closing the opening *a* leading to the valves of municipal water mains, not shown. The top 50 of the cover A is provided with a circumferential flange B having notches C which are usually spaced at an angle of ninety degrees from each other. A rather deep flange D depends from the top of the cover A to prevent the latter from becoming displaced in the top of the opening by 55 vehicles running over said cover.

Usually a tubular member E lines the opening leading to the valve to prevent the street or roadway from caving in at said opening. The upper margin of the tubular member E has an annular recess 24 for the reception of the circumferential flange B on the cover A.

In practice, when it is desired to lift the cover A from the opening as shown by Fig. 3, the jaws 12 and 18 are inserted in two diametrically opposed notches C and then caused to firmly grip 65 the cover A by tilting the rear end of the handle 4 upward slightly. Then by lifting the device 2 vertically the cover A may be raised straight upward so that the flange D will clear the interior of the tubular member E.

From the foregoing description it is apparent that I have provided a device which is well adapted for the purpose intended, and while I have shown one form of the invention I reserve all rights to such other forms and modifications 75 thereof as properly fall within the spirit and scope of the invention as claimed.

Having thus described my invention, what I claim and desire to secure by Letters Patent, is:

1. A device of the character described comprising a handle, an element mounted upon the forward end of said handle and having a downwardly extending portion terminating at its lower end in a jaw adapted to be inserted in a marginal notch in a cover, a member operably connected to the lower portion of said element, said member extending beneath the handle and terminating in a downwardly turned jaw adapted to enter a notch in the cover disposed diametrically opposite the first-mentioned notch, said 90 jaws being caused to grip and lift the cover when the handle is raised, and means for adjustably connecting said member to said element.

2. A device of the character described comprising a handle, an element secured to the forward end of said handle and having a downwardly extending portion provided at its lower end with a jaw, a member extending beneath the handle and provided at one end with a downturned jaw, the element and said member having 95 a plurality of apertures adapted to register with each other, and pivotal means adapted to pass through any of said apertures and operably connect the member to said element so that the jaws may be caused to grip an article between them 105 when the rear end of the handle is raised.

JOSEPH J. MOYLAN.
